UNITED STATES PATENT OFFICE

2,102,443

BUILDING CONSTRUCTION

Lawrence T. Thorn, Memphis, Tenn.

Application January 17, 1935, Serial No. 2,211

1 Claim. (Cl. 72—115)

This invention relates to a concrete construction which employs precast units and to the system whereby such units may be united together by the use of a filled in bonding concrete.

5 It further relates to a system of construction utilizing similar units and so adapting them that other types of units may be nailed thereto.

Among the objects of the invention are:

To provide a concrete stud for building construction which has on one or more faces or sides thereof, undercut slots adapted to receive and mechanically retain other concrete or material placed therein;

10 To provide slab units having on at least one side thereof undercut slots adapted to receive concrete or other type of material cast therein, and to be mechanically retained thereby;

15 To provide a method for securing a slab to a stud by filling abutting slot portions of both thereof with a bonding concrete or other material which will set and mechanically bond the slab to the stud;

20 To provide in a construction employing such studs; material cast in the slots on one or more faces thereof, adapted to receive and hold nails or the like driven thereinto, whereby lath or wall boards of various types or other devices may be directly nailed to such studs;

25 To provide a floor beam construction employing beams having particularly on their upper and under-surfaces, undercut slots adapted to receive nailing concrete or other material and/or a filling concrete adapted to mechanically bond other members to said beams;

30 To provide means for anchoring such studs to supporting foundations or supported parts and/or such beams to supporting members and/or wall surfaces abutting their ends, and for utilizing such tie-in means for reinforcing the studs or beams; and

35 To generally provide a building construction employing such studs and beams and slab construction.

In carrying out these objects, studs or beams are cast of concrete and are suitably reinforced for the purposes for which they are to be used. These studs or beams may be of any desired cross-section, preferably being either of rectangular or modified I-beam type. Where they are of rectangular type under-cut grooves are formed throughout their length in such sides and number of sides thereof as may be desired for the purposes to which they are to be used. Where the beams are of I-beam shape, ordinarily only the two opposed narrower faces are

so undercut. Wall slabs are similarly provided which are ordinarily provided on one of their faces with longitudinal slots or lines of slots. These slabs may be assembled against the face of the studs or beams with the slots of the slabs and beams facing and bonding concrete poured into the slots, which concrete after setting up mechanically anchors the two together.

5 When it is desired to nail on wall boards, lath or other things, as to form an interior of the wall or ceiling, the groove on the inner side of the stud, or under side of the beam, as the case may be, may be filled with concrete into which nails or the like may be driven or fastened and such surfacing materials be nailed or otherwise secured directly thereto.

10 The means by which the foregoing objects are accomplished and the manner of their accomplishment, will further readily be understood from the following specification on reference to the accompanying drawings, in which,—

15 Fig. 1 is a perspective view of a fragmentary portion of a stud and slabs assembled ready to receive a bonding concrete for securing the slab to the stud.

20 Fig. 2 is a fragmentary vertical sectional elevation showing manner in which the bonding concrete locks the slab to the stud.

25 Fig. 3 is a sectional plan showing a plurality of studs and slabs secured on opposite faces, but by different attaching means, one side of stud member being filled with a nail-receiving or nailing concrete and the other with bonding concrete and reinforcing clips joining stud and slab. This view also shows special shape of stud as for permitting attachment of door over window frames.

30 Fig. 4 is an enlarged view of one of the attaching or reinforcing clips.

35 Fig. 5 is a rear elevation of a slab showing the forms of undercut slots.

40 Figs. 6 and 7 are respectively a plan and transverse section of the slab shown in Fig. 5.

45 Fig. 8 is a vertical sectional elevation of a stud with slots on both sides, and showing method of attaching stud to foundations.

50 Fig. 9 is a sectional plan taken as on the line IX—IX of Fig. 8.

Fig. 10 is a similar section of the stud only.

55 Fig. 11 is an enlarged detail view of the horizontal joint between two slabs, showing a joint sealing element in place.

Fig. 12 is a sectional plan showing precast trim for window jambs and door jambs, and a frag-

mentary portion of a window sill, and the method of their attachment to the studs.

Fig. 13 is a similar sectional plan showing a door jamb and interior wall construction with 5 wall slabs nailed on.

Fig. 14 is a vertical sectional elevation taken as on the line XIV—XIV of Fig. 15, looking in the direction of the arrow.

Fig. 15 is a plan taken on the line XV—XV of 10 Fig. 14.

Fig. 16 is a sectional elevation taken as on the line XVI—XVI of Fig. 15, joist and stud being shown in elevation.

Fig. 17 is a plan view of precast plates used as 15 bottom forms for the ring beam.

Fig. 18 is a sectional plan of a modified form of stud, showing the bonding concrete filled between the ends of two wall slabs and anchoring these slabs to the stud.

Fig. 19 is a section plan view showing a modified means for securing the wall slabs to the studs, and showing interior wall slabs nailed to a composite stud.

Fig. 20 is a transverse sectional elevation of the 25 same wall taken as on the line XX—XX of Fig. 19.

Fig. 21 is an elevation of the stud and wall structure shown in Fig. 19.

Fig. 22 is a sectional plan of an interior partition wall and studs of single slab construction 30 in which a composite slab is used.

Fig. 23 is an elevation of a fragmentary portion of the wall shown in Fig. 22 showing an edge interlocking element and stiffener for the wall panels.

Fig. 24 is an enlarged fragmentary section taken as on the line XXIV—XXIV of Figs. 22 and 23, showing the edge interlocking element and stiffener.

Figs. 25 and 26 are respectively an edge and 40 plan view of the stiffener shown in Fig. 24.

Fig. 27 is a sectional elevation further enlarged taken on the line XXVII—XXVII of Figs. 25 and 26.

Fig. 28 is a sectional plan showing an interior 45 partition wall off set from a main wall stud.

Figs. 29 and 30 are sectional elevations showing an intermediate ceiling and floor construction and related stud construction.

Fig. 31 is a fragmentary sectional elevation 50 showing roof construction.

Fig. 32 is a sectional plan showing a modified stud construction of steel and concrete.

Fig. 33 is a sectional plan showing a modified construction in which a brick or stone, wall slab 55 is secured to the studs.

Fig. 34 is a corresponding elevation.

Fig. 35 is a sectional plan taken as on the line XXXV of Fig. 36, showing means and method of attaching monolithic concrete walls to precast 60 concrete studs.

Fig. 36 is a front elevation of a fragmentary portion of the stud and wall shown in Fig. 35.

Fig. 37 is a fragmentary sectional side elevation 65 taken as on the line XXXVII of Fig. 35.

Fig. 38 is a fragmentary transverse sectional elevation taken as on the line XXXVIII of Fig. 36.

Fig. 39 is an enlarged sectional plan of the form member used for forming the undercut slots and which form was shown on a smaller scale in 70 Fig. 35.

Fig. 40 is a sectional elevation taken as on the line XL of Fig. 41 showing spaced plates attached to precast slabs as forms for monolithic concrete studs.

Fig. 41 is a sectional plan on a reduced scale

of a plurality of studs and wall slabs taken as on the line XLI—XLI of Fig. 40, and

Fig. 42 is a corresponding sectional plan of one stud and adjacent wall slabs.

Fig. 43 is a section on the line XLIII of Fig. 40 5 showing fragmentary portions of form plates.

Fig. 44 is a perspective view of a form plate.

Fig. 45 is a transverse sectional elevation on the line XLV—XLV of Fig. 41.

Fig. 46 is an enlargement of a detail of the 10 plate shown in Fig. 43 and enclosed by the circle XLVI in Figs. 40 and 44.

Fig. 46A is a detail of the clip.

Fig. 47 is a sectional elevation taken as on the line XLVII of Fig. 48 showing a modification of 15 the structure shown in Fig. 40, using precast slabs on outer wall surface and insulating board and plaster as the inner surface.

Fig. 48 is a corresponding sectional plan on a 20 reduced scale.

Fig. 49 is a sectional elevation corresponding to Fig. 40 showing a further modification of the structure in which insulating board and plaster are used as surfacing for both sides of the wall.

Fig. 50 is a corresponding sectional plan on a 25 reduced scale.

Fig. 50A is a perspective view of a stiffener clamp shown in plan in Fig. 50.

Fig. 51 is an enlarged section of a column form 30 plate taken as on the line LI of Fig. 49.

Fig. 52 is a sectional elevation taken as on the line LII of Fig. 53, corresponding to Fig. 40 showing a further modification in which the outer wall surface is brick and the inner surface insulating board and plaster.

Fig. 53 is a corresponding sectional plan on a 35 reduced scale.

Fig. 54 is a fragmentary section taken as on the line LIV of Fig. 52 showing means for tying a stud forming plate to the brick wall.

Fig. 55 is a perspective view of the same parts 40 shown in Fig. 54.

Referring now to the drawings in which the various parts are indicated by numerals, 60 is a stud of generally I-beam form which may be 45 of plain concrete, or if desired, reinforced, as with suitable reinforcing rods 61. Opposite faces of the stud are provided with undercut grooves 62 usually of identical shape. The side walls 63 of these slots preferably extend inward from the 50 faces along substantially parallel lines for about one-half the depth of the slot and then diverge toward the back or bottom 64, thus making a slot in which concrete or mortar of some desired type may be placed and which concrete when it sets 55 up in the slot is mechanically keyed or tied thereto.

65 are slabs which are also shown of concrete. These slabs are provided on their inner faces with an undercut slot, or slots 66 which slots 60 are also adapted to be filled in with concrete or mortar, and which concrete or mortar will after setting, mechanically interlock with the slot. The slots 66 may extend continuously from end to end 65 of the slab as shown in Fig. 5; or a series of short slots 67 also shown in Fig. 5, may be used instead of one continuous slot. The slabs 65 are ordinarily made up in uniform lengths, which are a multiple of the stud spacing, which is to be used in any particular building construction. It is 70 found for instance that a two foot spacing of studs and four foot slabs are very convenient spacing and lengths respectively.

In such cases, where short slots 67 are used, the center to center spacing of these slots along the 75

length of the slab would be two feet, and the length of the slot on either side of such center spacing would be somewhat greater than that necessary to provide for the width of the stud 5 with which it is to be used, thus providing some leeway in the spacing of the studs. The upper edge of the slabs 65 are bevelled with the apex 68 of the beveling upward and the undersurface is provided with a complementary groove 69 adapted to receive on an underlying slab. The 10 ends of the slabs are preferably similarly bevelled.

70 is a reinforcing rod shown disposed in the slot 62.

In Fig. 2 the upper portion of the slot 62 and some of the slab slots 66 are shown prior to 15 pouring concrete therein. 71 is a reinforcing clip extending from one of the slab slots 66 into the stud slots 62. The lower portion of the slots 62 and the adjacent slab slots 66 are shown filled 20 with a bonding concrete 72 securing the slabs to the stud and which concrete when set up will, by its mechanical interlock in the slots, mechanically 25 tie the slab and stud together.

In Figs. 3 and 4 modified form 71A of the slot 30 reinforcement is shown. 72A is concrete adapted 35 to have nails, screws or the like driven thereinto and designated as nailing-concrete, which is filled into one slot 62 of the stud 60, into which concrete nails 73 may be driven to secure an insulating board 74 to the studs. 75 is a plaster finish on the insulating board 74. 60A is a modified form of studs 60 having an additional slot 40 62A which is filled with a nailing concrete 72A to receive and hold nails 76 by which a door jamb 35 77 or a window frame 78 may be secured to the side of the stud 60A.

Figs. 8 to 11 inclusive show slabs 65 secured to both faces of the stud 68 by bonding concrete 72 filled into the slab slots 66 and the stud slots 62 45 respectively and allowed to set. A strip of plastic material 79 preferably of bituminous nature may be placed between the top of each slab 65 and the underlying slab to form a water tight joint. 80 is a concrete foundation for supporting the studs 60 and wall slabs fastened thereto. The vertical reinforcing rods 70 may be anchored in this concrete foundation and extend upward therefrom, being bonded in the slots 62 when the bonding concrete filling is placed in the slots to 50 secure the slabs to the studs. Preferably the vertical joints 81 between the ends of any two slabs 65 comes at the center of a stud 60 so that the end joint thereof is sealed by the bonding concrete 72.

55 In Fig. 12 a precast concrete door jamb and trim 82 is shown locked to the studs 60A as by filled in bonding concrete 72. The door trim 82 may also be provided with an undercut slot 83 and this slot be filled with nailing concrete 84 to 60 permit an additional wooden portion 85 of the door trim to be secured thereto as by nails 86. 87 is a window sill, and 88 a window trim secured to nailing concrete 72 in the side slot of the stud 60A as by nails. 89 are panel boards secured 65 to the nailing concrete 72 in the studs by nails. Metal lath 90 (Fig. 13) may be similarly secured to the nailing concrete 72 of the studs.

In Fig. 14, shoulders 91 are shown on the upper ends of the studs 60. These shoulders support 70 precast plates 92 which in plan preferably are of the conformation shown in Fig. 17 and which serve as bottom forms for ring-beams 93. 94 are precast floor joists which are supported on the upper ends of the studs 60 and which preferably do not extend to the slab 65. These floor 75

joists are precast with holes 95 transversely thereto, through which holes reinforcing rods 96 may be placed. Additional reinforcing rods 97 extending around the ends of the floor joists may also be used if desired. With the floor joists, 5 supported on the studs and the form plates 92 also supported thereon, concrete is poured in place between the joists and around the ends thereof to form the ring-beam 93 and tie the structure into a unitary whole. Preferably the 10 vertical reinforcing rods 70 extend into or even above the top of the ring-beam.

A precast corner member 98 may be assembled 15 against the outer sides of the wall slabs 65 at the corner of two walls, and the space between the studs 60 and this corner member be filled in with monolithic concrete 99 to tie the structure together. The corner member 98 is provided with undercut slots 100 into which this concrete bonds, to mechanically tie the corner member to the 20 structure. Preferably the joists 94 are provided with suitable longitudinal reinforcement 101.

In Fig. 18 a modified type of stud 60B is shown 25 having undercut slots 62B and 62C. The wall slabs 65 are spaced apart at their ends and are 30 locked to the stud 60B by bonding concrete 102, filled between the ends of the slabs and into the slots 62C.

In Fig. 19 modified forms 60C and 60D of stud 35 are shown having one or more sides finished and 40 designed to be left exposed; these studs are provided with typical under-cut slots 62D, the studs being so placed for use that a slot of one stud faces a slot of the next stud. 65A are forms of 45 wall slabs of such length that their ends may be slipped into a facing pair of slots and after centering that they may be secured in such slots by bonding concrete filled thereinto. An interior wall surface may be preferably used, and may be 50 wall board 89 secured to the nailing concrete 72A as before described.

A similar type of construction is indicated in 55 Figs. 22 to 27 inclusive, in which studs 60C, 60E and 60F are used. In the construction there shown, insulating boards or the like 103 are secured in the facing slots of the studs and are secured therein by bonding concrete poured in place and thereafter the inner and outer surfaces of the wall are finished with plaster surface 104 on opposite sides thereof. To stiffen the insulating 60 board and secure the lower edge of one board in alignment with the upper edge of an adjacent board, metal plates 105 may be used, these plates preferably extending from stud to stud and having alternate triangular points 106, 107 extending 65 upward and downward respectively therefrom, these points being adapted to be embedded respectively in the under edges of the upper boards and in the upper edges of the lower boards.

Where as shown in Fig. 28 it is desired to put 70 in a transverse wall 108, other than in line with a stud 60, an additional stud 60G may be introduced at the desired point, the wall 108 or any of the other walls being of such typical construction as before described.

In Figs. 29 and 30, 94A are joists having nailing concrete 72A in their under-surfaces to which ceiling slabs 109 are secured as by nailing. 110 are floor slabs, the ends of which rest on the joists 94A, but are spaced apart to receive bonding concrete 111 which keys them together and to the top of the joists.

In Fig. 29 a stud 60 for supporting an upper 75 floor or roof is shown supported on a pair of the joists 94A. The lower end of the stud is shoul-

dered to leave a downwardly extending center portion 112 which extends preferably slightly below the floor slabs 110 and into the space between the two joists. Vertical reinforcing rods 5 70A in the stud grooves 62 extend below the end of the studs and into the space between the joists. After the stud is set up the space between the joists and around the lower end 112 of the stud and the reinforcing rod 70 is filled with the bonding 10 concrete 111 to tie the studs to the joists.

In Fig. 30 a stud 60, supports the joists 94A, the reinforcing rod 70A in the stud groove 62 extending upward and being bonded to the joists 94A by the bonding concrete 111.

15 In Fig. 31, 94B is a roof joist or rafter directly supporting a roof structure. 113 are roof slabs having undercut grooves 114 therein which grooves are filled with nailing concrete 115, these slabs extending from joist to joist as do the floor 20 slabs 110 in Fig. 30, their ends being spaced apart as there shown. They are secured to the joists by filling the space between the ends with bonding concrete 111A, this concrete keying into the grooves 94C of the joists. 116 is roofing material 25 such as slate or shingles nailed directly to the nailing concrete of the roof slabs.

In Fig. 32 a modified form 60B of stud is shown in which the shell of the stud is made up of two structural channels 117 assembled with their 30 flanges 118 facing, the channels being secured together by an intermediate structural member 119 welded to the channel webs. The member 119 divides the stud into two sections which as shown are respectively filled on the one side with nailing 35 concrete 120 and on the other side with bonding concrete 121, the latter concrete being filled in after the wall slabs 65 are placed to lock these wall slabs in place. 89 is the wall board secured to the nailing concrete 120 by nails 73.

40 In Fig. 33 a stone wall-slab 122 is secured to a stud 60 by bonding concrete 72. To effect the securing of this slab, a slot 123 is channeled in the back of the slab, and this slot, together with the undercut groove 62 is filled with the bonding 45 concrete 72. 124 are reinforcing clips imbedded in the concrete. 125 are brick laid up in courses. 126 is a reinforcing rod extending lengthwise of these courses. 127 are reinforcing clips laid between courses of brick and extending into the 50 grooves 62 of the stud 60, these grooves as before, being filled with bonding concrete to bond in the reinforcing clips.

Figs. 35 to 39 inclusive, illustrate construction methods which may be employed in utilizing the 55 studs in connection with a monolithic wall. 128 are horizontally disposed stringers to which form planks 129 are secured. 130 are blocks spacing the form planks 129 from the studs 60. 131 are vertically disposed wooden posts which are bolted to U shape clamps 132, these clamps each extending around a stud 60. 133 are form planks secured to the post 131 and extending from stud to stud. 134 are tie rods or bolts tieing the studs 131 to the horizontal stringers 128. The outer 60 ends of the bolts 134 are slotted to receive wedge shaped keys 135. These forms are set up and monolithic wall concrete 136 is cast in place in the forms, the concrete keying into the undercut groove 62 of the studs.

70 In forming the undercut grooves 62 in the studs 60 or forming similar undercut grooves in the monolithic concrete for later use, a core is made up as shown in Fig. 39. This core comprises a beveled edged core part 136 of soft rubber shaped to form the undercut portion of the 75

groove, and a strip 137 which may be of metal or wood, and is preferably given a slight taper to allow its easy withdrawal from the concrete.

In making use of this core it is set up as shown in Fig. 35 and bolted directly against the form 5 133 with which it is to be used. After the concrete has been poured and set up, the core pulls out as the form is removed the pliability of the inner rubber portion permitting its removal.

Figs. 40 to 46 inclusive, show another method 10 of tying together wall slabs, formed with key slots therein. In this modification column forms are set up between the wall slabs 65, having the undercut slots 66 therein.

In these modifications 140 are rectangular metal 15 plates having a width equal to the desired spacing between wall slabs and preferably a height equal to the width of the wall slabs. These plates have one edge formed with flanges 141 thereon, from which flanges clips 142 are formed which 20 clips are adapted to enter the undercut grooves 66. These clips are preferably formed initially as shown in the enlarged view Fig. 46, of such width from point to point that they will enter the grooves 66. After entering the grooves 66 25 the plate is forced against the slab 65, spreading the points of the clips to the position 142A also there shown and thereby interlocking the clips with the grooves. The top and bottom edges of the plates 140 are divided into three equal parts. 30 The outer two of these 143 on the top edge are bent laterally to one side of the plate and the center one 144 to the opposite side thereof. The bottom lugs 145 and 146 are bent in opposite and complementary manner, so that when two plates 35 are assembled one above the other, such plate lugs will interlock and prevent separation, and the plates will tie the wall slots together.

These plates 140 are set up between the slabs in pairs spaced apart to give the desired column 40 size and the space between the two plates filled in, the concrete 147 forming the column and interlocking directly with that portion of the undercut slab slots 66 lying between the plates, and also spreading along the slots past the plates 45 to surround and imbed the clips 142.

In Figs. 47 to 51 inclusive, a construction similar to that above described is shown except that the construction is modified to use the insulating board 74 and plaster 75 in connection with oppositely disposed wall slabs 65. In this construction, plates 140A have clips 142 formed thereon as before, but the opposite edges of the plates have spaced flanges 150, 151 turned at right angles thereto which flanges are adapted to engage the end edges of the boards 74 and tie the oppositely disposed wall slabs together. These plates may also have upwardly and downwardly turned lugs 152 and 153 on their bottom and top edges respectively engaging the bottom and 60 top edges of the board 74.

154 are clip plates having spaced lugs 155, 156, adapted to engage the upper edges of wall boards 74 intermediate column forms for stiffening purposes during construction.

In Figs. 52 to 55 inclusive, a further modification is shown in which one wall surface is formed of brick. In this modification one edge of the plate 140B has alternating oppositely disposed flange portions 160, 161, extending at right angles therefrom. 162 is a retaining member having inwardly turned flanges 163 which form grooves 164 adapted to receive the flanges 160, 161 of the plate 140B, the plate flanges being engaged with the groove 164 by sliding them down- 75

ward therein. The retaining member 162 has a 5 backwardly turned clip portion 165, at its upper end, which clip portion is imbedded in the mortar joint 166 between two courses of brick 167 as the courses are laid up. The flanges 160, 161 of the plates 140B when interlocked with the retaining members secure the plates 140B against lateral displacement and also tie the brick wall to the inner insulating board and plaster wall 10 74, 75. The column spaces formed as before, by two sets of the plates 140B is filled in with concrete to form the column or stud. Preferably the plates have holes 168 therethrough which members such as reinforcing rods or pipes for carrying 15 wiring may be passed should it be so desired. These holes where not in use to permit passage of other things permit the concrete being placed to extrude and thereby tie the plates to the column.

20 In making use of the present invention in its preferred form a number of concrete studs 60 of desired length or height are made of concrete with undercut grooves 62 in opposite faces thereof, or such other form of stud, such as the 25 studs 60A or the studs 60C and 60D with two or more undercut grooves are similarly made and allowed to set and harden. Such floor beams 94, 94A and roof beams or joists 94B with the desired number of undercut grooves therein are 30 also made up. Where it is intended to nail wall slabs or other members to such stud beams or joists, such grooves of these members as are to receive nails or the like are filled with the concrete of some well known type, which will permit 35 nails to be driven therein without cracking of the concrete and such filling is allowed to set and harden. Also where it is desired to make use of a structure of column such as is illustrated in Fig. 32, such portion of column as is to 40 be nailed to is filled with a suitable nailing concrete.

Wall slabs 65, floor slabs 110 and roofing slabs 113 are also made up of such desired width and 45 length as may be desired with suitable undercut grooves extending continuously throughout their length, or shorter grooves properly spaced preferably in continuous lines. Where other articles are to be nailed to these slabs such as roofing as shown in Fig. 31 the slab grooves are filled 50 with a suitable nailing concrete and this also allowed to set and harden. Such accessories and parts as window sills 81 and door frames 82 and/or other parts as may be needed are also made up ready for use.

55 Preferably a concrete foundation is laid down, such reinforcing rods 70 as it may be desired to use being embedded therein and allowed to project thereabove, the spacing of these rods being made to conform to the desired stud spacing or 60 other spacing for the purposes for which they may be required. The wall studs 60 or other variant forms of such stud as are to be used are set up on the concrete foundation with the reinforcing rods in the grooves thereof and are 65 suitably plumbed and braced. The first row of wall slabs 65 on one or both sides of such studs, usually however on the outer side only, are set up on the concrete foundation with their grooved sides facing the studs and are suitably clamped 70 thereto in any desired manner, a suitable cushion or seat of mortar being provided both for studs and slabs. Freshly mixed bonding mortar or concrete, usually of rather fluid consistency is then filled into the vertical groove 62 on one side 75 of the stud and flows or is worked downward

in the groove to the bottom of the slab. Such mortar or concrete thus placed spreads out into the grooves 66 of the slabs filling them in front of the groove in the stud, and usually spreads laterally along the slot somewhat beyond the 25 sides of the studs. Where there are slabs on both sides of the stud this operation is repeated on the opposite side.

When the first course of slabs, or such portion of such course as desired, has been secured to 10 the studs, a second course of slabs is seated on the first course, a plastic filler 79 preferably being interposed to fill the joint though of course other type of filler may be used if desired. This second row of slabs is clamped in place and the 15 operation of grouting together as above described is repeated.

Where it is desired to reinforce the joints between the stud and slab, the reinforcing clips 20 71, or 71A are of course placed before the bonding concrete or mortar is filled in. It will be noted that some of these forms of clips when so placed will secure the slab to the stud temporarily during the placing of the bonding concrete.

Where precast slabs are used on one side of the wall only, such other wall slab as the plaster board 74, to be later finished with a plaster surface 75, or the wall board 89, is nailed directly 30 to the nailing concrete 72A of the stud.

In that form of the wall shown in Fig. 19, the grooves of the studs 60C and 60D which are to receive the wall slab 65A are aligned with the line of the wall with one groove of each stud facing an opposed groove of the next stud. One end of a wall slab 65A is slipped into a groove as the groove 62D of the stud 60C and the opposite end moved into alignment with the groove 62D of the stud 60D. The wall slab is then shifted until its ends lie partially in the 40 grooves of the two studs and thereafter such grooves are filled with bonding concrete to secure the slab and the operation repeated. The interior wall surface 89 is then placed and nailed, 45 as before described.

The same operation is carried out with respect to the insulating board 103 in Fig. 22, except that preferably after the first insulating board is placed a stiffening and reinforcing member 105 is placed on top of such board and the downwardly projecting points 107 are driven into the top of the board. A superposed board of the wall is then placed and driven down on the upwardly extending points 106 of the member 105. After completing the desired height of the 50 wall the interior and/or exterior surface thereof may be plastered as shown.

Where stone slabs, tile slabs, or the like are used in place of the concrete slab, the procedure is identical with that of the concrete slab. Where a brick wall surface is to be laid up along the studs, one or more courses of brick as shown in Fig. 34 are laid up. When the mortar is placed to receive an additional course, reinforcing clips 65 127, one for each stud are embedded in such mortar with the clips extending into the groove 62 of the stud, and at least one additional course of brick is laid up. Bonding concrete is then placed in the grooves 62 of the studs up to the 70 level of such latter course of brick and thereafter the operation repeated. Where it is desired, additional clips as the clip 27 may be placed at the wall corner and the space between the studs 60 and the brick courses be filled up 75

either during the laying of the brick or after the completion of the wall.

When the wall has been built up by any of the variations of the method hereinbefore described, floor beams 94 or ceiling beams, are placed on top of the studs 60 and the space between and around the ends of these beams is filled in with concrete to form a ring beam 93. Preferably shoulders 91 have been formed on the studs 60 and pre-cast slabs 92 are supported on such shoulders to provide a form for the bottom of the ring beam, though such bottom form might be otherwise made and supported if it were so desired. Preferably also the outer wall slabs 65 are carried above the top of the ring beam to provide the outer form therefor, and the inner wall surface 89 may also be carried up for the same purpose, such reinforcing as is desired may be used and incorporated with the ring beam concrete which is filled in between the beams 94 after they have been thus placed.

After the floor beams have been placed and set, the ceiling 109 may be nailed directly to the nailing concrete 72A on the underside thereof as shown in Fig. 29, the floor slabs 110 may be laid on the beams and the bonding concrete 111 filled in between the ends thereof and into the beam groove 62 to tie the floor slabs to such beams.

The roofing slabs 113 are placed on the roofing joints 94B as are the slabs 110 on the beams 94A of Fig. 30, and are secured to the joists by filling in between the ends thereof by bonding concrete 111A. The roofing surface 116 may then be

nailed directly to the nailing concrete 115 of these roofing slabs.

In carrying out the construction shown in Figs. 40 to 46 inclusive, two rows of wall slabs 65 are set up and spaced apart by placing therebetween a form plate 140, securing the clips 142 of the form plate in the grooves 66 of one wall slab, and allowing the other side of the plate to abut the other slab. A second form plate is then set up at such distance from the first form plate as is desired to give the desired size of column, this second plate having its side edges reversed with respect to the first form plate so that its clips will engage the grooves of the opposite row of slabs. Two superposed courses of slabs are placed, one course on each of the first rows and form plates set up between the slabs of these courses. Each of the form plates so placed is reversed with respect to the plate therebelow with its bottom lugs interlocked with the lugs of the plate below and its clips in the abutting wall slab, thus forming a tie against lateral separation of the wall slabs. Concrete 147 is then filled in to the top of the first row of slabs, an additional double course of slabs placed and the operations repeated.

What I claim is:

A unit for building construction, comprising a precast concrete member having an undercut groove formed in a face thereof, the outer portion of said groove having sides extending inward substantially at right angles to the face of said member for substantially one half its depth, and thence diverging to the bottom of said groove.

LAWRENCE T. THORN. 35
